CLAIM

The ornamental design for an electronic document reader, as shown and described.

DESCRIPTION

FIG. 1 is a front elevational view of an embodiment of the electronic document reader of the present design;

FIG. 2 is a rear elevational view of the electronic document reader of FIG. 1;

FIG. 3 is a left side elevational view of the electronic document reader of FIG. 1;

FIG. 4 is a bottom side elevational view of the electronic document reader of FIG. 1;

FIG. 5 is a front, left side, and bottom side perspective view of the electronic document reader of FIG. 1 in an unfolded configuration;

FIG. 6 is a front, left side, and bottom side perspective view of the electronic document reader of FIG. 1 in an angled configuration; and,

FIG. 7 is a front, left side, and bottom side perspective view of the electronic document reader of FIG. 1 in a folded configuration.
